UNITED STATES PATENT OFFICE.

HAROLD E. SLADE, OF NEWARK, NEW JERSEY, ASSIGNOR TO BEAVER MACHINE & TOOL COMPANY, INC., OF NEWARK, NEW JERSEY, A CORPORATION OF NEW JERSEY.

ELECTRIC-LAMP SOCKET.

Application filed December 7, 1923. Serial No. 679,051.

This invention relates to an electric lamp socket and more particularly to the keyless type of electric lamp socket. Heretofore, so far as I am aware, it has been customary in the manufacture of keyless electric lamp sockets to connect the screw thread terminal and in many structures also the center terminal to the base of the lamp socket by screws or bolts which pass into or longitudinally through the base of the socket. The parts of the socket involved in this construction are attached to the base with more or less difficulty as well as being unnecessarily numerous. One of the objects of my invention, therefore, is to overcome this difficulty by simplifying the construction as well as the manner of assembling and connecting the parts by providing a screw socket terminal adapted in part at least to span a portion of the socket base and to be connected thereto by a member passing transversely through the base. The construction is also such that one of the line terminals and the center contact are also connected to the base by a member transversely associated with the base. In the construction of keyless lamp sockets, as heretofore manufactured, various means have been employed for attaching the cap to the shell so as to be readily removable therefrom and to prevent the base and parts associated therewith from turning relatively to the shell and its cap. The present invention also includes a simplified structure for accomplishing this purpose which structure includes suitable apertures provided in the peripheral portion of the cap adapted to be engaged by bosses provided for this purpose on the peripheral portion of the shell together with a notch in the edge of the shell adapted to receive a lug on the casing to prevent a relative turning movement between these parts, the said notch being continued in the shell in the form of a centrally disposed slot of sufficient extent to provide the required resiliency in the end of the shell for compressing the same in separating the cap therefrom. These and other features of my improved keyless socket will be hereinafter more particularly described.

In the drawing.

Fig. 1 is an elevation of my improved

keyless electric lamp socket illustrating a part of the cover or cap broken away to show the formation of the notch and slot in the shell.

Fig. 2 is an elevation of the base and parts associated therewith.

Fig. 3 is an enlarged central longitudinal section.

Fig. 4 is a plan of the socket with the cap removed, and

Fig. 5 is an inverted plan with the shell removed.

Referring to the drawings, the socket made in accordance with this invention includes the usual shell 10 and the cap member 11 adapted to fit over one end of the shell to be connected thereto. As illustrated, the cap 11 is provided with a series of spaced apertures 12 which are preferably semi-circular and the peripheral portion of the shell at one end thereof is provided with a corresponding number of bosses 13 each of which is preferably semi-spherical and each adapted to engage in one of the openings 12 to secure the cap in position on the shell. Also as illustrated the cap may be provided with a plurality of indentations 14 adapted to engage the peripheral portion of the insulating lining 15 employed in the cap.

As is customary the shell 10 is provided with an insulating lining 16 which may be made of any suitable material for the purposes intended. The shell is adapted to receive a base and the electrical conducting members associated therewith as hereinafter described and at the cap end of the shell a notch 17 is provided in the periphery thereof to receive a lug, as hereinafter described, on the base member to prevent the relative rotation of these parts. The peripheral portion of the shell is cut away in a substantially rectangular configuration to provide the notch 17. At the inner end of the notch the same includes recesses 18 extending circumferentially of the shell and the notch also includes a centrally disposed V-shaped slot 19 extending longitudinally of the shell a sufficient distance to make the adjacent portions of the shell resilient enough to be compressed to readily effect the removal of the cap when this is necessary or desirable, it being understood

that when the parts are in position the peripheral portion of the cap is prevented from participating in this resilient action through the lug on the base, as hereinafter described. Furthermore the edge portions of the shell at the notched end thereof are inturned to provide ears indicated at 20 and 21 and the corresponding portions of the insulating lining with ears 22 and 23 for en-

10 gaging the sides of the lug on the base.

The base of the lamp socket is indicated at 24 and as is customary this is made of porcelain or any other similar and equally good insulating material. The base is fitted with a screw socket terminal 25 adapted to receive the screw terminal of a lamp bulb and provided with oppositely disposed longitudinally extending lugs 26 and 27 adapted respectively to be received in and to lie 15 against the bases of the recesses or grooves 28 and 29 provided therefor in opposite positions in the base 24. The socket is also provided with lead wire terminals, one of which is indicated at 30 and is fitted with 20 a binding screw 31 adapted to engage a lead wire 32 to secure the same in position against the terminal 30. Also as illustrated the terminal 30 lies in the recess 29 and is provided with a boss adapted to be received 25 in an opening provided therefor in the lug 27. A tie-bolt 33 passes through an opening provided therefor in the lug 26, passes transversely through a bore provided for 30 this purpose in the base 24 and at its opposite end is threaded to engage a tapped opening in the lead wire terminal 30 to secure these parts together.

The central contact of the socket is indicated at 34. This is made integral with a 40 lead wire terminal 35 which passes through an opening 36 provided in the walls of the screw socket contact 25 for this purpose so that the central contact 34 may assume a central position relatively to the screw 45 socket contact and the base. The other end of the lead wire terminal 35 lies in a recess 37 provided in the side of the base for this purpose, the recess 37 being separated from the recess 28 by a wall 38 extending from 50 the body of the base. The lead wire terminal 35 is provided with a binding screw 39 adapted to engage the end of a lead wire 40 for securing the same to the lead wire terminal. This lead wire terminal 35 is secured in position, being connected to the base 24 by a tie-bolt 41, the head of which lies in a recess 42 while the shank extends through a transverse bore provided in the base 24 for this purpose in order to permit 55 the screw threaded end of the tie-bolt to engage a tapped opening in the lead wire terminal by which engagement, as will be understood, the lead wire terminal is maintained in position.

60 As clearly seen in Fig. 5 the screw socket

contact 25 is provided with an inturned end portion 43 adapted to lie against the inner end of the base 24 and is notched to engage the sides of a lug 44 projecting from the inner end of the base in order to assist in 70 maintaining the relative positions of these parts and for the same purpose on the opposite side the screw socket contact 25 is provided with an inturned end 45, the edges of which are adapted to engage a lug 46 at 75 the inner end of the base 24.

In a suitable position preferably that in which the lead wire terminals and the binding screws thereof will be spaced equally distant from the notch 17, the base 24 is 80 provided with a rib 47 in the upper or outer end of which there is a lug 48 adapted to extend through and to lie within the notch 17 to prevent a rotary shifting of the base and its associated parts relatively to 85 the shell. The peripheral portions of the base 24 adjacent the rib 27 are preferably flattened faces as indicated at 49 and 50 for the purpose of providing said rib and effecting an economy in the use of the material from which the base is made. Similarly on the opposite side of the base there is a rib 51 which, however, is not provided with a corresponding lug, but on either side of which the base has flattened faces 52 and 53, while adjacent the flattened face 53 there is a flattened face 54 along which the longitudinal portion of the lead wire terminal 35 extends.

From the foregoing description it will be 100 understood that the number of parts of the socket is reduced to a minimum and the facility with which the parts may be assembled is increased by making it possible to pass the tie-bolt transversely through the base to secure the terminal and contact members in position, while the shell and base are maintained in their relative places and the shell is made sufficiently resilient to permit of the ready removal of the cap by being 105 depressible on either side of the lug which, when the parts are in place, maintains the peripheral portion of the cap in position by preventing the same from being depressed.

I claim as my invention:

1. In an electric lamp socket, an insulating base, a lamp terminal screw contact having lugs extending therefrom adapted to engage substantially oppositely disposed faces provided therefor on the said base, a lead wire terminal having a boss thereon adapted to enter a recess provided therefor in one of the said lugs, and a unitary means passing through the said base transversely, and engaging one of the said lugs to secure the said lamp terminal screw contact to said base, and also engaging the said lead wire terminal to secure the same and the other of the said lugs to the said base.

2. In an electric lamp socket, an insulat-

- ing base, a lamp terminal screw contact having lugs extending therefrom adapted to engage substantially oppositely disposed faces provided therefor on the said base, a lead wire terminal having a boss thereon adapted to enter a recess provided therefor in one of the said lugs, a unitary means passing through the said base transversely, and engaging one of the said lugs to secure 5 the said lamp terminal screw contact to said base, and also engaging the said lead wire terminal to secure the same and the other of the said lugs to the said base, a lamp terminal center contact having an extension 10 adapted to lie against a face provided therefor on the said base, and means also passing transversely through the said base for engaging the said extension to fix the same and 15 the said lamp terminal center contact thereto. 20
3. In an electric lamp socket, an insulating base, a lamp terminal screw contact having lugs extending therefrom adapted to engage substantially oppositely disposed faces provided therefor on the said base, a lead wire terminal adapted to contact with one of the said lugs of the lamp terminal screw contact, and a unitary means passing through said base transversely and engaging one of the lugs to secure the said lamp terminal screw contact to said base and also 25 engaging the same lead wire terminal to secure the same and the other of the said lugs to the said base. 30

Signed by me this 20th day of Sept., 1923.

HAROLD E. SLADE.
